UNITED STATES PATENT OFFICE

2,093,216

COOLING APPARATUS

Ernest F. Stalcup, Rutledge, and Millard A. Nelson, Prospect Park, Pa., assignors to Westinghouse Electric & Manufacturing Company, East Pittsburgh, Pa., a corporation of Pennsylvania

Application October 11, 1933, Serial No. 693,194

17 Claims. (Cl. 62—152)

Our invention relates to refrigerating apparatus, more particularly to apparatus of the type known as steam jet refrigerating apparatus, and it has for an object to provide improved apparatus of this type which is adapted for operation at partial load.

Apparatus of this type includes a chamber in which a vacuous or reduced pressure condition is maintained by an ejector or compressor, exhausting usually to a condenser. Liquid to be cooled, usually water, is circulated or conveyed through the chamber, the reduced pressure therein effecting evaporation of a portion of the liquid and consequent cooling of the remaining liquid, which may then be used as refrigerating medium or to provide a supply of cooled liquid. A steam ejector is not always sufficiently adaptable to change in load, and is usually operated at full load, that is, with full admission of motivating 20 steam or other fluid.

In order to provide economy of operation at partial load, it has been proposed to provide a plurality of evaporating chambers, each of which has an ejector to effect a reduced pressure condition by withdrawing vapor therefrom. The refrigerant liquid is distributed among the several evaporating chambers. For operation at partial load, one or more ejectors is shut off, the remaining ejector or ejectors continuing to operate at full capacity. Refrigeration is then effected in only some of the evaporating chambers. This presents the problem of supplying full quantity of refrigerant liquid, which is necessary in some cases. In air conditioning apparatus comprising sprays, for example, a given quantity of cooling liquid is required to maintain the sprays, regardless of the refrigerating load.

In accordance with our invention, for operation at partial load, we divert the flow of liquid from the evaporating chambers whose ejectors are shut down, to the evaporating chamber or chambers whose ejector or ejectors remain in operation.

With this arrangement, the full quantity of liquid is refrigerated. Consequently, it is not necessary to cool the liquid to the same degree as in the arrangement in which only a portion of the refrigerant is cooled, and a substantially higher efficiency is obtained. For example, assume that refrigerant at 40 degrees F. is required and that it is returned from the point of use at 42½ degrees F. If half the liquid is refrigerated, it is necessary to cool to 37½ degrees F., in order to reduce the total quantity to 40 degrees, whereas if all the liquid is refrigerated, it is only nec-

essary to reduce the temperature to 40 degrees F. Cooling to 40 degrees F. can be accomplished at substantially higher efficiency than cooling to 37½ degrees F., with the same total amount of heat removed in each case.

The apparatus shown and described in this application to illustrate our invention also embodies an invention described and claimed in the application of Paul L. Fetzer, Serial No. 659,402, filed March 2, 1933, namely, the manometric connection or loop seal hereinafter described.

The above and other objects are effected by our invention as will be apparent from the following description and claims taken in accordance with the accompanying drawings, forming a part of this application, in which:

Fig. 1 is a diagrammatic elevation view of one embodiment of the refrigerating apparatus;

Fig. 2 is a plan view of the same embodiment showing the ejectors and the common condenser; and

Fig. 3 is a diagrammatic elevational view of a second embodiment of the refrigerating apparatus.

Referring now to the drawings more in detail, we show steam jet refrigerating apparatus for supplying cooled liquid, such as water, to any apparatus in which it may be required. Such apparatus may be, for example, the air cooler and washer of air conditioning apparatus, shown on the drawings at 9.

The refrigerating apparatus (Figs. 1 and 2) comprises a primary evaporating chamber 10 and a secondary evaporating chamber 11. In the present embodiment, these chambers are formed by separate tanks. Steam ejectors 12 and 13, shown in Fig. 2, have their suction inlets 12' and 13' connected to the chambers 10 and 11, respectively, and effect a vacuous or reduced pressure condition in the respective chambers by withdrawing vapor therefrom. The ejectors 12 and 13 are motivated by steam from a supply conduit 14, the admission thereof being controlled by valves 15 and 16, respectively, the operation of which is described later. The ejectors exhaust into a common condenser 17, which is provided with a condensate outlet 18, an air outlet 19 connected to an air ejector 20, a cooling water inlet 21 and a cooling water outlet 22.

For full load operation, both ejectors are operated. For partial load operation, only the ejector 12 is operated, the ejector 13 being shut down by closing the valve 16. The condenser pressure is then admitted into the chamber 11 through the ejector 13.

The water to be cooled is conveyed, in this case from the air cooler, by a conduit 23 to the evaporating chamber or chambers. The water is divided, one portion being admitted always to spray nozzles 24 in the chamber 10. The remaining portion is admitted by a valve 25 either to a second group of spray nozzles 26 in the chamber 10, for partial load operation, or to spray nozzles 27 in the chamber 11, for full load operation. Upon being subjected to the vacuum or decreased pressure in the evaporating chamber, the water is partially evaporated, which action effects cooling of the remaining water, as is well known in the art.

The water cooled in each evaporating chamber is discharged therefrom through an outlet in the bottom, the bottom preferably converging toward the outlet. The outlets are connected to a system of conduits, which, is, in accordance with the said invention of Paul L. Fetzer, arranged to provide a manometric connection or loop seal between the chambers to seal the chamber 10 against the higher absolute pressure in the chamber 11 at partial load operation. This conduit system includes separate branch discharge conduits 28 and 29 communicating with the chambers 10 and 11, respectively, and with a common discharge conduit 31. The conduit 29 is of smaller diameter than the conduits 28 and 31, as it never conveys more than a portion of the water, while the conduit 28 conveys the full quantity of water at partial load. The conduits 28 and 29 extend first downwardly and then communicate at a low level through horizontally extending portions, thereby providing the manometric connection or loop seal between the chambers 10 and 11. The conduit 28 is of sufficient height to provide a head of liquid "a" which opposes the increase in pressure in the chamber 11 at partial load. The water is then conveyed by the conduit 31, to a pump 32, by which it is forced through a conduit 33 to the air cooler 9 or other refrigerating load. In the latter, the cooled water is used for cooling and washing air. Obviously, the cooled water may be used as refrigerating medium for any desired purpose. Its temperature having been increased, it is discharged from the air cooler to the conduit 23 and recirculated.

Control mechanism for regulating the operation of the refrigerating apparatus is provided. It includes solenoids 34 and 35 for opening valves 15 and 16, respectively, the latter being biased to closed position by the weight of the core. A solenoid 36 controls the valve 25, which is biased to the position in which it admits water to the nozzles 26 in the chamber 10, and is operated to admit water to the nozzles 27 in the chamber 11 when the solenoid 36 is energized. The solenoid 34 is controlled by contacts 38. The contacts 37 and 38 are controlled by a thermostat 39 in response to the temperature of the liquid to be cooled at any desired point in its circuit or path. Preferably, and as shown, the thermostat includes an expansible bellows 41 connected by a tube 42 to a bulb 43 disposed in the conduit 31. The thermostat 39 is arranged to close the contacts 37 in response to a predetermined maximum temperature, to close both contacts 37 and 38 in response to a slightly higher predetermined maximum temperature, and to open both contacts 37 and 38 in response to a temperature lower than the first-mentioned predetermined maximum temperature. For the purpose of an example, the first and second pre-

determined maximum temperature will be taken as 40° and 41° F., respectively.

Make-up water to replace the water which is vaporized and removed is supplied through a conduit 44. It is preferably first cooled in one of the evaporating chambers, and hence the conduit 44 may be connected to the conduit 23. The admission of make-up water is controlled by a valve 45, which is controlled by a float control 46 in response to the level of water in the chamber 10.

The operation of the above-described apparatus is as follows:

When the air cooler or other refrigerating load requires the maximum amount of refrigeration, this is evidenced by a temperature of the circulating water of 41° F. or higher. The thermostat 39 closes contacts 37 and 38, rendering both ejectors operative, and adjusting the valve 25 to admit water to the chamber 11. Approximately one-half of the water, or any other desired portion, is admitted to the chamber 11, and the remaining portion to the chamber 10. The water is cooled or refrigerated in the respective chambers as above described, substantially the same degree of vacuum or pressure being maintained therein. The water is discharged in parallel through the conduits 28 and 29 to the conduit 31, and supplied to the air cooler.

As the requirement for refrigeration decreases, the temperature of the water decreases. However, the contacts 38 will be kept closed and the apparatus maintained at full load operation until the temperature drops below 41° F., indicating that half load operation will supply the needed refrigeration, at least temporarily. The contacts 38 are then opened, deenergizing the solenoids 35 and 36. The ejector 13 is shut down and the valve 25 diverts the water from the chamber 11 to the chamber 10. Due to the shutting down of the ejector 13, the pressure in the chamber 11 will rise to that in the condenser 17, lowering the level of the water in the conduit 29, until the difference in head between the column of water in the conduit 28 and the bottom of the chamber 10 and the water in the conduit 29, indicated by the reference character "a", balances the difference between the absolute pressures in the two evaporating chambers. The full quantity of water then flows through the chamber 10, the branch discharge conduit 28 and the common conduit 31, while the water in the branch discharge conduit 29 remains stationary. It is to be noted that the higher pressure in the chamber 11 tends to heat the water, but as the level of the water is down in the conduit 29, the amount of surface of water subject to heating will be negligible.

If the refrigeration requirement is substantially less than full load, and greater than half load, there will be intermittent full load and half load operation, the temperature of the water decreasing during the full load operation and increasing during the half load operation.

If the temperature of the water drops below 40° F., indicating that no further refrigeration is presently needed, the contacts 37 are also opened, shutting down the ejector 12. The water is then circulated through the chamber 10 without any cooling except for the action of the air ejector 20 of the condenser, which effects a small amount of evaporation of the water and consequent cooling. Upon subsequent increase in temperature of the water, the contacts 37 will reclose, and cooling at half load is resumed. Thus, a load

less than half load is taken care of by intermittent half-load operation.

With the above-described apparatus, the same quantity of cooled water is supplied at half load as at full load, this being necessary to maintain the sprays in the air cooler and washer. By diverting the water from the chamber 11 to the chamber 10, all of the water is refrigerated, thereby supplying water of uniform temperature. As above pointed out, this operation is more efficient, since the temperature reduction is less than would be necessary if only a portion of the water were cooled.

In Fig. 3, we show a second embodiment of our invention which is similar to the first embodiment, except that the evaporating chambers and conduits are arranged for flow of water to be cooled successively through the evaporating chambers when operating at full load, instead of parallel flow. In this case, the evaporating chamber 11' constitutes the primary chamber, or the chamber first in series. It is disposed at a higher elevation than the evaporating chamber 10', and its outlet is connected through a looped conduit 51 to the inlet of the chamber 10'. All of the water delivered by the conduit 23 passes through the valve 25 in this case, and is directed thereby to the inlet of the chamber 11', at full load and to the inlet of the chamber 10' through a conduit 52 at half load. The same control mechanism used in the first embodiment may be provided.

At full load operation, effected by the thermostat 39 closing contacts 37 and 38 in response to the higher maximum temperature of 41° F., both ejectors are operated and the valve 25 directs all the water to the chamber 11'. In the latter, the water is partially cooled, preferably one-half of the temperature reduction being effected in this chamber. The water then flows by gravity through the conduit 51 to the chamber 10', the difference in level between the chambers providing sufficient pressure head to force the water through the nozzles in the chamber 10'. The remainder of the temperature reduction of the water is effected in the chamber 10', and the water is then discharged therefrom into a conduit 31'.

At half load operation, the control mechanism operates, as in the first embodiment, to shut down the ejector 13 and to adjust the valve 25 to direct all the water into the chamber 10'. The apparatus then operates identically with half-load operation of the first embodiment, the looped conduit 51 providing a loop seal against the higher condenser pressure in the chamber 11'.

With the multi-stage apparatus of Fig. 3, greater efficiency of operation is obtained. This is due to the fact that the portion of the refrigeration action effected in the first stage is at a higher temperature, which, as is well known in the art, is effected more economically.

While we have shown our invention in several forms, it will be obvious to those skilled in the art that it is not so limited, but is susceptible of various other changes and modifications, without departing from the spirit thereof, and we desire, therefore, that only such limitations shall be placed thereupon as are imposed by the prior art or as are specifically set forth in the appended claims.

What we claim is:

1. The method of refrigerating which comprises admitting and distributing a predetermined quantity of liquid to be cooled to a plurality of chambers at full load, admitting substantially

said predetermined quantity of liquid to fewer of said chambers at partial load, and exhausting vapor from each chamber to which liquid is supplied.

2. The method of refrigerating which comprises admitting a predetermined quantity of liquid to be cooled to and dividing the same among a plurality of evaporating chambers and maintaining a reduced pressure condition in all of said chambers at full load, and admitting substantially said predetermined quantity to a smaller number of said chambers and maintaining a reduced pressure condition in said smaller number of chambers at partial load, whereby substantially the same quantity of cooled liquid is provided at full and partial loads.

3. The method of refrigerating which comprises supplying a predetermined quantity of liquid to be cooled, dividing said quantity among a plurality of evaporating chambers for operation at full load, admitting said predetermined quantity to a smaller number of said chambers for operation at partial load, maintaining a reduced pressure condition in each chamber to which liquid is admitted to cool said liquid by partial evaporation thereof, and discharging said liquid from said chamber or chambers to provide a predetermined quantity of cooled liquid at either full load or partial load operation.

4. The method of refrigerating which comprises admitting a predetermined quantity of liquid to one or more of a plurality of evaporating chambers and discharging the cooled liquid therefrom, dividing said predetermined quantity of liquid among said chambers and exhausting vapor therefrom in response to a predetermined maximum temperature of the liquid, and admitting substantially said predetermined quantity of liquid to a lesser number of chambers and exhausting vapor therefrom in response to a lower predetermined maximum temperature of the liquid.

5. In refrigerating apparatus of the vapor jet type, the combination of a plurality of evaporating chambers, an ejector connected to each chamber for effecting a vacuous condition therein, and means for passing a given quantity of refrigerant selectively through several evaporating chambers or through a smaller number of said chambers.

6. In refrigerating apparatus, the combination of a plurality of evaporating chambers, means for effecting a reduced pressure condition in said chambers to provide partial evaporation of liquid therein, means for admitting a predetermined quantity of liquid to be cooled to one or more of said chambers, and means whereby said predetermined quantity of liquid may be either divided among said chambers or admitted to one thereof.

7. Refrigerating apparatus of the vapor jet type comprising a plurality of evaporating chambers, means for effecting a reduced pressure condition in said chambers to provide partial evaporation and cooling of liquid therein, means for distributing a predetermined quantity of liquid to be cooled to said chambers, means for diverting the liquid from one of said chambers to another thereof for operation at reduced load, and means for removing the cooled liquid from said chamber or chambers, whereby the same quantity of cooled liquid is provided at different loads.

8. In refrigerating apparatus, the combination of a first and a second evaporating chamber, means for effecting a reduced pressure condition in said chambers, means for supplying a predetermined quantity of liquid to be cooled, means

- for admitting one portion of said quantity of liquid to the first chamber and means for admitting the remaining portion selectively to either the first or the second chamber.
5. 9. Refrigerating apparatus of the vapor jet type comprising a first and a second evaporating chamber, means for effecting a reduced pressure condition in said chambers to effect partial evaporation and cooling of liquid therein, means 10 for supplying liquid to be cooled to said chambers, said first and second chambers having inlets adapted to admit substantially the same quantity of liquid to be cooled, a valve adapted to place either one of said inlets in communication with 15 said liquid supply means, the first chamber having a second inlet in communication with said liquid supply means, and means for discharging cooled liquid from said chamber or chambers.
10. In refrigerating apparatus, the combination 20 of a plurality of evaporating chambers, means for conveying a predetermined quantity of liquid through said chambers to be cooled, means for dividing said predetermined quantity of liquid among a plurality of said chambers and 25 for effecting a reduced pressure condition therein in response to a predetermined maximum temperature of said liquid, and means for admitting said predetermined quantity of liquid to a smaller number of said chambers and effecting a reduced 30 pressure condition therein in response to a lower predetermined maximum temperature.
11. In refrigerating apparatus, the combination 35 of a plurality of evaporating chambers, an ejector for each chamber for producing a reduced pressure condition therein to provide partial evaporation and cooling of liquid, means for supplying a predetermined quantity of liquid to be cooled, means for distributing said predetermined quantity of liquid to a plurality of said chambers 40 and for effecting operation of the ejectors connected thereto in response to a predetermined maximum temperature of the liquid being cooled, and means for admitting said predetermined quantity of liquid to a smaller number of chambers and for effecting operation of the ejector or 45 ejectors connected to said smaller number of chambers in response to a lower predetermined maximum temperature of the liquid being cooled.
12. In refrigerating apparatus, the combination 50 of a first and a second evaporator chamber, an ejector connected to each chamber for effecting a vacuous condition to provide partial evaporation and cooling of liquid therein, a conduit for supplying liquid to be cooled, each of said chambers having an inlet of substantially the same capacity 55 for admitting liquid to be cooled, a valve for placing either one of said inlets in communication with the liquid supply conduit, said first chamber having a second inlet communicating with the liquid supply conduit, means responsive to a predetermined maximum temperature of the 60 liquid being cooled for effecting operation of both ejectors and actuating the said valve to admit liquid to the second chamber, and means responsive to a lower predetermined maximum temperature of the liquid being cooled for effecting operation of the ejector connected to the first chamber and for actuating said valve to place the first-mentioned inlet of the first chamber in communication with the liquid supply conduit.
13. In vapor jet apparatus for providing a supply of cooled liquid, the combination of a plurality of evaporating chambers, an ejector 10 connected to each chamber for withdrawing vapor therefrom to effect cooling of liquid therein by partial evaporation, and means for circulating liquid selectively through several evaporating chambers or through a smaller number of said chambers to provide said supply of cooled liquid. 15
14. In refrigerating apparatus, the combination of a plurality of evaporating chambers, means associated with each chamber for withdrawing vapor therefrom to effect cooling of liquid in the 20 chamber by partial evaporation of the liquid, and means whereby a given quantity of liquid may be selectively passed through and cooled in several of said evaporating chambers or passed through and cooled in a smaller number of said chambers. 25
15. In refrigerating apparatus, the combination of a plurality of evaporating chambers, a fluid translating element connected to each chamber for reducing the pressure therein to provide partial evaporation and cooling of liquid therein, 30 means responsive to the cooling demand for rendering said elements individually operative or inoperative, and means for conveying a substantially constant quantity of liquid through only the chamber or chambers whose fluid translating 35 elements are rendered operative.
16. In refrigerating apparatus, the combination of a plurality of evaporator chambers, a fluid translating element connected to each chamber to provide partial evaporation and cooling of 40 liquid therein, means for supplying liquid to be cooled to said chambers, and valve means controlling flow of liquid to be cooled and operative to shut off flow of liquid to one chamber and simultaneously to increase the flow of liquid to 45 another chamber.
17. In refrigerating apparatus, the combination of a plurality of evaporator chambers, an ejector connected to each chamber to provide partial evaporation and cooling of liquid therein, means for supplying liquid to be cooled to said chambers, and means operative in response to increase 50 in temperature of the cooled liquid above a predetermined value to render a plurality of said ejectors effective and operative in response to 55 decrease in said temperature below said value to render one of said last-mentioned ejectors ineffective, to terminate admission of liquid to be cooled to the associated chamber, and to increase the admission of liquid to be cooled to another 60 chamber whose ejector remains effective.

- for admitting one portion of said quantity of liquid to the first chamber and means for admitting the remaining portion selectively to either the first or the second chamber.
5. 9. Refrigerating apparatus of the vapor jet type comprising a first and a second evaporating chamber, means for effecting a reduced pressure condition in said chambers to effect partial evaporation and cooling of liquid therein, means 10 for supplying liquid to be cooled to said chambers, said first and second chambers having inlets adapted to admit substantially the same quantity of liquid to be cooled, a valve adapted to place either one of said inlets in communication with 15 said liquid supply means, the first chamber having a second inlet in communication with said liquid supply means, and means for discharging cooled liquid from said chamber or chambers.
10. In refrigerating apparatus, the combination 20 of a plurality of evaporating chambers, means for conveying a predetermined quantity of liquid through said chambers to be cooled, means for dividing said predetermined quantity of liquid among a plurality of said chambers and 25 for effecting a reduced pressure condition therein in response to a predetermined maximum temperature of said liquid, and means for admitting said predetermined quantity of liquid to a smaller number of said chambers and effecting a reduced 30 pressure condition therein in response to a lower predetermined maximum temperature.
11. In refrigerating apparatus, the combination 35 of a plurality of evaporating chambers, an ejector for each chamber for producing a reduced pressure condition therein to provide partial evaporation and cooling of liquid, means for supplying a predetermined quantity of liquid to be cooled, means for distributing said predetermined quantity of liquid to a plurality of said chambers 40 and for effecting operation of the ejectors connected thereto in response to a predetermined maximum temperature of the liquid being cooled, and means for admitting said predetermined quantity of liquid to a smaller number of chambers and for effecting operation of the ejector or 45 ejectors connected to said smaller number of chambers in response to a lower predetermined maximum temperature of the liquid being cooled.
12. In refrigerating apparatus, the combination 50 of a first and a second evaporator chamber, an ejector connected to each chamber for effecting a vacuous condition to provide partial evaporation and cooling of liquid therein, a conduit for supplying liquid to be cooled, each of said chambers having an inlet of substantially the same capacity 55 for admitting liquid to be cooled, a valve for placing either one of said inlets in communication with the liquid supply conduit, said first chamber having a second inlet communicating with the liquid supply conduit, means responsive to a predetermined maximum temperature of the 60 liquid being cooled for effecting operation of both ejectors and actuating the said valve to admit liquid to the second chamber, and means responsive to a lower predetermined maximum temperature of the liquid being cooled for effecting operation of the ejector connected to the first chamber and for actuating said valve to place the first-mentioned inlet of the first chamber in communication with the liquid supply conduit.
13. In vapor jet apparatus for providing a supply of cooled liquid, the combination of a plurality of evaporating chambers, an ejector 10 connected to each chamber for withdrawing vapor therefrom to effect cooling of liquid therein by partial evaporation, and means for circulating liquid selectively through several evaporating chambers or through a smaller number of said chambers to provide said supply of cooled liquid. 15
14. In refrigerating apparatus, the combination of a plurality of evaporating chambers, means associated with each chamber for withdrawing vapor therefrom to effect cooling of liquid in the 20 chamber by partial evaporation of the liquid, and means whereby a given quantity of liquid may be selectively passed through and cooled in several of said evaporating chambers or passed through and cooled in a smaller number of said chambers. 25
15. In refrigerating apparatus, the combination of a plurality of evaporating chambers, a fluid translating element connected to each chamber for reducing the pressure therein to provide partial evaporation and cooling of liquid therein, 30 means responsive to the cooling demand for rendering said elements individually operative or inoperative, and means for conveying a substantially constant quantity of liquid through only the chamber or chambers whose fluid translating 35 elements are rendered operative.
16. In refrigerating apparatus, the combination of a plurality of evaporator chambers, a fluid translating element connected to each chamber to provide partial evaporation and cooling of 40 liquid therein, means for supplying liquid to be cooled to said chambers, and valve means controlling flow of liquid to be cooled and operative to shut off flow of liquid to one chamber and simultaneously to increase the flow of liquid to 45 another chamber.
17. In refrigerating apparatus, the combination of a plurality of evaporator chambers, an ejector connected to each chamber to provide partial evaporation and cooling of liquid therein, means for supplying liquid to be cooled to said chambers, and means operative in response to increase 50 in temperature of the cooled liquid above a predetermined value to render a plurality of said ejectors effective and operative in response to 55 decrease in said temperature below said value to render one of said last-mentioned ejectors ineffective, to terminate admission of liquid to be cooled to the associated chamber, and to increase the admission of liquid to be cooled to another 60 chamber whose ejector remains effective.
